UNITED STATES PATENT OFFICE.

WILLIAM H. REMSEN, OF KANSAS CITY, MISSOURI, ASSIGNOR OF ONE-HALF TO
GEORGE HEINEMANN, OF KANSAS CITY, MISSOURI.

TRUCK HOIST.

Application filed July 21, 1921. Serial No. 486,479.

To all whom it may concern:

Be it known that I, WILLIAM H. REMSEN, a citizen of the United States, residing at Kansas City, in the county of Jackson and 5 State of Missouri, have invented certain new and useful Improvements in Truck Hoists, of which the following is a specification.

My invention relates to improvements in 10 hoists for raising the bodies of motor trucks to dumping position and for lowering such bodies after the loads have been dumped.

One object is to provide a new, compact 15 and powerful mechanism of this character which can be readily installed on a motor truck and geared to the engine of such truck, so that the truck body can be raised and lowered by power instead of resorting to manual labor.

20 A further object is to provide new and useful means for automatically throwing the hoisting mechanism out of gear when the truck body reaches the end of its upward and downward movements, and thus avoid 25 damage to the mechanism by neglect of the driver to throw it out of gear.

Other objects will hereinafter appear and 30 in order that the invention may be fully understood, reference will now be had to the accompanying drawings, in which:

Fig. 1 is a broken side elevation of a motor truck equipped with the hoist.

Fig. 2 is an irregular vertical section of 35 the hoist and a portion of the truck, taken on line II—II of Fig. 3.

Fig. 3 is an irregular vertical section taken on line III—III of Fig. 2.

Fig. 4 is a fragmentary plan view, partly 40 in section, of a portion of the throw-out mechanism.

Fig. 5 is a fragmentary section of part of 45 the mechanism disclosed by Fig. 2.

Fig. 6 is a fragmentary vertical section of 50 a modified form of the throw-out mechanism.

Fig. 7 is a fragmentary vertical section of another modified form of throw-out mechanism.

Fig. 8 is a fragmentary vertical section of 55 another modified form of throw-out mechanism.

A, designates a motor truck equipped with the usual chassis B and body C, which latter is mounted adjacent its rear end on pivots D

carried by said chassis B. All of the foregoing is of usual construction.

Referring now more particularly to the parts constituting the present invention, 2 designates an upright housing provided with 5 bearings 4 at its lower portion in which a 10 drum shaft 6 is journaled. Said drum shaft 6 is equipped with a fixedly-mounted centrally disposed worm wheel 8 and drums 10 and 12 disposed at opposite sides of said 15 worm wheel 8. Cables 14 and 16 for raising 20 and lowering the body C are attached to the drums 10 and 12, respectively, and the arms 25 28 fixed to the front end of the body C.

The cables 14 and 16 run around guide 30 rollers 20 and guide sheaves 22 and 24. The 35 guide rollers 20 are journaled in brackets 25 secured to opposite sides of the housing 2, and the guide sheaves 22 and 24 are journaled in brackets 26 having tubular shanks 30 journaled in the upper end of the housing 2. As shown on Fig. 2, the tubular portions of the brackets 26 are substantially in vertical alignment with the front margins of the sheaves 22, so that the same may swing 40 freely with the brackets 26 without changing the position of that portion of the cables 45 14 and 16 extending from the respective drums 10 and 12 to said sheaves 22. The free ends of the brackets 26 are supported by 50 braces 27, mounted at their lower ends on 55 pivots 29, fixed to a bar 31 in the housing 2.

The worm wheel 8 is driven in both directions to effect the raising and lowering of the truck body C, from the propeller shaft 55 E, through a train consisting of a sprocket 60 wheel 34 driven by the sprocket wheel 32 through a chain 36, a sprocket wheel 38 fixed to the hub 40 of the sprocket wheel 34, a sprocket wheel 42 driven by the sprocket 65 wheel 38 through a chain 44, a cog wheel 46 70 fixed to the hub 47 of the sprocket wheel 42, a cog wheel 48 driven by the cog wheel 46, a worm 54, a worm wheel 56 driven by the worm 54, a worm 58, an intermediate clutch 75 member 60, and clutch members 62 and 64, 80 on the hubs of the wheels 38 and 48, respectively. The hubs of the wheels 38 and 48, are spaced apart and loosely mounted upon 85 a shaft 66 journaled in bearings 68 and upon which the worm 54 is fixedly mounted. The 90 intermediate clutch member 60 is splined 95 upon the shaft 66 and disposed between the clutch members 62 and 64, so that it can 100 105

readily engage either. Coil springs 70 interposed between the ends of the intermediate clutch member 60 and the companion clutch members 62 and 64, yieldably hold said intermediate clutch member 60 in neutral position.

The intermediate clutch member 60 is shifted into engagement with either of the companion clutch members 62, 64, to effect 10 the raising or lowering of the truck body C, by a lever 72 fulcrumed at 74 and manually controlled through the intermediacy of a connecting rod 76 and a hand lever 78 which latter is arranged adjacent to the driver's 15 seat.

The lever 72 is automatically actuated to throw the intermediate clutch member 60 to neutral position to stop the truck body C as it reaches dumping position, through the intermediacy of a connecting rod 75, a crank arm 79, a shaft 80 to which said crank 79 is fixed, crank arms 82 fixed to the shaft 80, links 84 pivoted to the free ends of the crank arms 82, rods 86 pivoted to the free ends of 25 the links 84, brackets 88 having eyes through which the rods 86 freely extend, and nuts 90 threaded upon the upper ends of the rods 86 and engaged and raised by the brackets 88 as the body C approaches the end of its upward movement; until the links 84 raise the 30 crank arms 82 sufficiently to shift the intermediate clutch member 60 to neutral position, as above stated.

The lever 72 is automatically actuated to 35 shift the intermediate clutch 60 to intermediate position to stop the truck body C as it reaches the end of its downward movement, through the intermediacy of the same mechanism which actuates said lever 72 to stop 40 the body C on its upward movement, excepting that a crank 92 and a member 96 actuate the shaft 80 instead of the cranks 82, the links 84, the rods 86, the nuts 90, and the brackets 88. The crank 92 is fixed to 45 the shaft 80, while the member 96 is fixed to the underside of the body C, so that when said body approaches the end of its downward movement the member 96 will contact the free end of the crank 92 and rock the 50 same downwardly, thereby causing the intervening mechanism to shift the clutch member 60 to neutral position, as above stated.

The nuts 90 may be adjusted up or down on the rods 86 to be engaged at the proper time by the brackets 96, and the crank 92 is 55 adjustably mounted on the shaft 80 to be engaged by the member 96 at the proper time.

In the modified form Fig. 6, the construction and operation are substantially the same 60 as in the preferred form, excepting that the rods 86^a, operate in tubes 15, secured at their lower ends by hinges 17 to the front of the body C'. As the body C' is raised to dumping position the nuts 90^a are engaged by the 65 associated hinges 17 and raise the rods 86^a, causing them to throw the intermediate clutch member 60 to neutral position.

In Fig. 7, a chain or chains 86^b are substituted for the rods 86, and in Fig. 8 a spool 100 and a cable 102 are substituted for the crank 92 and the member 96. The spool 100 is secured to the drum shaft 6 and a cable 102 is wound thereon as the body C^b moves downwardly, said cable 102 being of 75 such length as to actuate the shifting mechanism and cause it to throw the clutch member 60 to neutral as the body C^b reaches the end of its downward movement.

In addition to the foregoing I reserve the 80 right to make such other modifications as fall within the spirit and scope of the claim.

Having thus described my invention, what I claim and desire to secure by Letters Patent, is:

In combination with a motor vehicle having a dump body, a support mounted on said vehicle in front of the body, a drum journaled on said support, brackets located above said drum and having tubular shanks swiveled in said support, a pair of sheaves journaled in each bracket, cables attached at their ends to the drum and the body to raise and lower the latter and running through the respective tubular shanks and over the 95 sheaves, and mechanism for rotating the drum in either direction.

In testimony whereof I affix my signature, in the presence of two witnesses:

WILLIAM H. REMSEN.
